DESIGN FOR A JUICE EXTRACTOR

Henry J. Talge, Kansas City, Mo., assignor to
John C. Hockery, Foster L. Talge, and Henry J.
Talge, doing business as Rival Manufacturing
Company, Kansas City, Mo.

Application October 16, 1944, Serial No. 115,806

Term of patent 14 years

(Cl. D89—1)

To all whom it may concern:

Be it known that I, Henry J. Talge, a citizen
of the United States, residing at Kansas City,
Jackson County, State of Missouri, have invented
a new, original, and ornamental Design for a
Juice Extractor, of which the following is a speci-
fication, reference being had to the accom-
panying drawing, forming part thereof, in which

Fig. 1 is a side elevational view of a juice
extractor embodying the new design,

Fig. 2 is a front elevational view of the juice
extractor shown in Fig. 1, and

Fig. 3 is a top plan view thereof.

I claim:

The ornamental design for a juice extractor,
substantially as shown.

HENRY J. TALGE.
